UNITED STATES PATENT OFFICE

DIETRICH GLEIM, OF HASTINGS, MINNESOTA.

HAME ATTACHMENT.

No. 842,400.

Specification of Letters Patent.

Patented Jan. 29, 1907.

Application filed October 16, 1906. Serial No. 339,249.

To all whom it may concern:

Be it known that I, DIETRICH GLEIM, a citizen of the United States, residing at Hastings, in the county of Dakota and State 5 of Minnesota, have invented a new and useful Hame Attachment, of which the following is a specification.

This invention has relation to hame attachments; and it consists in the novel construction and arrangement of its parts, as hereinafter shown and described.

The object of the invention is to provide a hame attachment with a vertically-adjustable tug in order that the connecting-point 15 between the trace and the hame may be adjusted as conditions may require. At the same time the hame-tug is free to swing horizontally with relation to the hame, and thus the means of attachment between the hame 20 and the trace does not interfere with the movement of the shoulders of the draft-animal.

In the accompanying drawings, Figure 1 is a side elevation of a hame fitted with my attachment. Fig. 2 is a vertical sectional view 25 of the attachment.

The hame 1 is provided with the spaced eyes 2 2. The bolt 3 is seated at its ends in the openings of the eyes 2 2. The sleeve 4 is 30 journaled upon the bolt 3 and bears at its ends against the sides of the eyes 2 2. The trace-clip 5 comprises the horizontally-disposed eye 6 and the vertically-disposed loop 7. The trace (not shown) is adapted to be

attached to the loop 7. The eye 6 receives 35 the sleeve 4, and the said eye is provided with a set-screw 8, which engages at its inner end the surface of the sleeve 4. The said eye 6 may be adjusted longitudinally of the sleeve 4 and secured in such adjusted position by 40 means of the set-screw 8. By this means it will be observed that the point of attachment between the trace and the hame may be adjusted vertically, and by reason of the fact that the sleeve 4 is journaled upon the 45 pin 3 the said sleeve and trace-clip may swing laterally with relation to the hame.

Having described my invention, what I claim as new, and desire to secure by Letters Patent, is—

In combination with a hame, spaced eyes attached thereto, a bolt seated at its end in the openings of the eyes, a sleeve journaled upon the bolt and bearing at its ends against the sides of the eyes, a trace-clip having a 50 horizontally-disposed eye which receives said sleeve and which is capable of longitudinal movement thereon, said clip-eye having a seat screw, said clip having a vertically-disposed loop for attachment with the trace.

In testimony that I claim the foregoing as my own I have hereto affixed my signature in the presence of two witnesses.

DIETRICH GLEIM.
